UNITED STATES PATENT OFFICE.

ARMON H. KING AND ALFRED E. KING, OF CLAYVILLE, NEW YORK.

HAY ELEVATOR AND CARRIER.

SPECIFICATION forming part of Letters Patent No. 299,800, dated June 3, 1884.

Application filed April 23, 1884. (No model.)

To all whom it may concern:

Be it known that we, A. H. KING and A. E. KING, both citizens of the United States and residents of Clayville, in the county of Oneida and State of New York, have invented certain new and useful Improvements in Hay Elevators and Carriers; and we do hereby declare that the following is a full, clear, and exact description of the invention, which will enable others skilled in the art to which it appertains to make and use the same, reference being had to the accompanying drawings, which form a part of this specification, and in which—

15 Figure 1 is a perspective view of our improved hay elevator and carrier. Fig. 2 is a longitudinal vertical section of the same. Fig. 3 is a perspective detail view of the stop, and Fig. 4 is a similar view of the several parts of 20 the stop separated.

Similar letters of reference indicate corresponding parts in all the figures.

Our invention has relation to hay elevators and carriers; and it consists in the improved 25 construction and combination of parts of the same, as hereinafter more fully described and claimed.

In the accompanying drawings, the letter A indicates the rod or rope upon which the 30 carriage travels, which consists of two side pieces, B, forming a bell-shaped flange, C, at their lower edges, and in which the pulleys D which travel upon the rod are journaled, between the upper edges of the side pieces.

35 E is an eye to which one end of the elevator-rope is secured, with its headed shank, F, between two lips G, having each a notch, H, in their edges, which notches clasp the shank and hold it, allowing it to swivel in the 40 bearing formed by them. These lips are in one end of the lower edges of the side pieces, and a pulley, I, is journaled in the other end, over which pulley the rope passes after having passed through the block J, to which the 45 fork is attached. The upper portion of the block J is provided with the usual headed shank, K, which is held by the catch L when the block is hoisted up to the carrier and has been guided by the bell-shaped flange into the 50 catch. The catch L consists of an irregularly-shaped block pivoted upon a bolt, M, passing

through the side pieces, and the edge of the block is recessed at one side, as shown at N, adapted to receive the headed shank of the hoisting-block, and the lower end of this recess is slotted longitudinally at O, the slot being open at the outer side, so that the shank of the hoisting-block may slide into the slot, while the head of the shank will be too large to pass through the same, and will bear against 55 the inner side of the slotted side, holding the block and its load supported.

For the purpose of preventing the catch-block from turning upon its bolt when the headed shank is caught in it, the block has an upwardly-facing shoulder, P, upon the side opposite to the recess, and the lower end of a trigger-block, Q, will engage the said shoulder when the headed shank is caught, the lower end of the trigger-block being weighted and 65 the block being pivoted above and slightly to one side of the catch-block. The upper end of the trigger-block is beveled upon the inwardly-facing side, and a weighted catch-block, R, is pivoted above and to the other 70 side of the catch-block L, having its inwardly-pointing end weighted and its outwardly-pointing end turned slightly upward, forming an inwardly-beveled catch, S. A stop, T, is secured to the end of the rope or track above 75 the place where the hay is unloaded, and consists of a long block, U, having a beveled catch or shoulder, V, at its outer end, and having a shoulder, W, near its inner end, and the upper side of the said block has a longitudinal 80 groove, X, which fits around the rope or rod forming the track. The inner end of the long block inside the shoulder is provided with a longitudinal rib or feather, Y, which fits into a longitudinal slot, Z, in the 85 outer end of a block, A', having a recess, B', in its upper side which clamps the underside of the long block and two laterally-projecting ears, C', one of which has a female threaded 90 perforation, D', while the other ear has a perforation, E'. A block, F', having two laterally-projecting ears, G', fits with its recess H' over the rope or rod forming the track and over the upper side of the long block, clamping the said track and the block between it, 95 and the lower block having the ears, and one of the ears of the upper block forms a down-

wardly and outwardly projecting hook, I', which fits into the smooth perforation in the ear of the lower block, being caught in it, and the other ear has a female threaded perforation, J', into which fits and turns a screw, K', which turns in the threaded perforation of the ear of the lower block, the said screw serving to draw the two clamping-blocks together after the hook has been inserted into the perforation in the ear of the lower block, clamping the long block and the track.

When the carrier rests upon the track over the load to be unloaded, the outer beveled shoulder of the long stop-block T bears with its inner side against the upturned end of the weighted catch-block R, thus preventing the carrier from moving away from its position, and the weighted end of the trigger-block Q will catch against the shoulder upon the recessed catch-block L when the shank of the hoisting-block has entered the recess in the catch-block and been caught by the slotted lower side of the recess. When now the hoisting-rope is pulled for the purpose of drawing the carrier along the track to the place where the load is to be dumped, the shank of the hoisting-block is forced to bear against the upper side of the recess in the catch-block, tilting the upper portion of the said block upward and slightly outward, and the said upper portion being eccentric and of a larger radius than the other portions of the block, it will raise the weighted end of the weighted catch-block, lowering the outer end of the same sufficiently to allow it to pass under the shoulder upon the outer end of the stop-block, allowing the carrier to pass freely to its destination.

Having thus described our invention, we

claim and desire to secure by Letters Patent 40 of the United States—

1. In a hay elevator and carrier, the combination of the stop-block having a beveled shoulder at its outer end and a shoulder at its inner end, with the carrier having the recessed 45 catch-block provided with an upwardly-facing shoulder, the weighted trigger-block having the beveled upper end, the weighted catch-block having the upwardly-turned outer end, and the hoisting-block having the headed shank, the upper portion of the catch-block being the most eccentric, as and for the purpose shown and set forth.

2. The stop for the track of a hay carrier and elevator, consisting of the long block having a beveled shoulder at its outer end, a shoulder having a longitudinal rib at its inner end and a longitudinal groove in its upper side, the lower clamping-block having a slot in its outer end and provided with a laterally-projecting ear having a threaded perforation, and a laterally-projecting ear having a smooth perforation, the lower clamping-block having a laterally-projecting ear provided at its outer end with a downwardly and outwardly projecting 60 hook, and a laterally-projecting ear having a threaded perforation, and the screw passing through the threaded perforations, all constructed and combined as and for the purpose shown and set forth.

In testimony that we claim the foregoing as our own we have hereunto affixed our signatures in presence of two witnesses.

ARMON H. KING.
ALFRED E. KING.
